UNITED STATES PATENT OFFICE.

GEORGE O. BERGSTROM, OF NEENAH, WISCONSIN, ASSIGNOR TO BERGSTROM STOVE CO., OF NEENAH, WISCONSIN, A CORPORATION OF WISCONSIN.

WOODEN FLASK.

Application filed November 7, 1924. Serial No. 748,342.

To all whom it may concern:

Be it known that I, GEORGE O. BERGSTROM, a citizen of the United States, residing at Neenah, county of Winnebago, and 5 State of Wisconsin, have invented new and useful Improvements in Wooden Flasks, of which the following is a specification.

This invention relates to improvements in wooden flasks.

10 Wooden flasks as heretofore constructed have had the advantage of light weight but have usually been cheaply built, inadequately secured together, and have been very shortlived, due to rotting at points where 15 the wooden sides of the flasks overlapped for the purpose of nailing.

It will be understood that moulding sand is damp and that the continual dampness, together with heat, causes the wooden sides 20 of the flasks to deteriorate rapidly, particularly at the joints.

I have found that the above difficulties can be overcome simply and economically to produce a long-lived wooden flask, through 25 the medium of fittings which will even outlive the side members of the flask and may be used with new side members to construct additional flasks after the original device is no longer useful. It is the primary object 30 of this invention to provide a novel and improved type of flask having the above mentioned advantages.

In the drawings:

Figure 1 is a plan view of a two-part flask 35 embodying this invention.

Figure 2 is a side elevation of the flask shown in Figure 1.

Figures 3 and 4 are detail views of fittings employed in the construction of a flask of 40 this character.

Like parts are identified by the same reference characters throughout the several views.

It will be noted that the side walls of each 45 part of the flask are made of wood. The walls include side members 5 and 6 and end members 7 and 8. These members are hereinafter to be termed generically the sides of the flask.

50 Applied to each corner of the flask are angular fittings including an internal fitting 9 and an external fitting 10. Diagonally disposed bolts 12 secure these fittings together in pairs, each of which includes an inner and an outer fitting. It will be ob-

vious that each pair of fittings so secured embraces two contiguous sides of the flask to retain them in their desired relative position. Seats may conveniently be provided at 13 and 14 upon the inner and outer flasks, respectively, to receive a flush bearing contact from the nuts 15 and 16 of bolt 12.

Where the flasks are subjected to considerable pressure it is desirable to increase the strength of the connection between the pairs 65 of clamps and the wooden sides of the flasks. This may conveniently be done by providing either the inner or outer clamps, or both, with studs 20 which are best shown in Figure 3, and which are indicated in dotted 70 lines in Figure 1. These studs are received in apertures provided for the purpose in the sides of the flasks and provide a positive connection which secures the sides against separation. Thus, the inner and outer 75 clamps not only exert a binding or clamping action upon the sides but may also conveniently be connected positively with the sides.

It is particularly to be noted that the 80 areas in the corners of the flasks are left unobstructed for the free circulation of air. There is no overlapping of the wooden sides of the flask at the corners thereof, and the interior and exterior clamps are so 85 formed as to leave the corners open. This fact is of great importance, since I have found that by facilitating and encouraging air circulation across the exposed ends of the side members of the flask the effect of 90 rot becomes greatly decreased and the side members will be comparatively long-lived. It is the ends of such members, where the grain is exposed, that are particularly subject to rot, and if the flask is constructed 95 in the manner heretofore common in the art, there is a constant accumulation of water at the ends of the flask sides so that decay is continuous at these points. In the present device the air circulation which is afforded, due to the construction of the side members and of the clamps, tends to carry away any moisture from these points and to prevent any accumulation of moisture.

So far as the above description goes the 105 cope and the drag of the flask are identical in construction. Each may be regarded as a complete article by itself. Where the two parts are used together, however, it is easy to attach fittings to the exterior clamping 110

members for ensuring the accurate seating of the cope upon the drag. To this end bolt apertures are provided at 21 in the exterior clamping member 10, both of the 5 cope and of the drag. Bolts passed through these apertures are used to secure to the clamping members 10 of the drag, upon one end thereof, the members 22 which include offset tapered studs 23. To the corresponding 10 end of the cope are fastened angles 24 having laterally projecting arms 25 which receive the tapered studs 23 attached to the drag. The curvature of the studs is such as to enable them, with arms 25, to permit 15 the function of a hinge, whereby the cope and drag are detachably connected.

At the opposite ends of the cope and drag the bolts passed through apertures 21 may serve, in the case of the drag, to support a fitting having a laterally projecting 20 arm 27 with a hemispherical boss 28, whereas the clamping member 10 attached to the cope has an arm 29 provided with a hemispherical recess adapted to receive the boss 25 28. These devices are self centering and ensure the accurate alignment of the cope and drag.

It is to be noted that the construction of the parts herein described is standardized 30 both for the reason that the castings applied to the cope and drag as clamping devices are identical, and for the further reason that these castings are provided with apertures at such points as interchangeably to 35 receive the several fittings 22, 24, 27, and 29. Thus, the parts cannot only be economically manufactured and assembled but they are accurate and serviceable and, due to the long life afforded to the wood sides 40 by the provision of air circulation across the ends of the side members, the devices combine lightness in weight with great durability. The objects specified for the invention, therefore, are satisfied by the disclosure herein.

I claim:

1. In a device of the character described, the combination of wooden sides arranged to comprise a substantially closed figure and 50 having exposed ends with closely adjacent corners, together with metallic means connecting said sides with their ends exposed as aforesaid, said means comprising internal and external angular clamps applied to the 55 exterior and interior portions of contiguous sides adjacent their respective ends, each external clamp aforesaid being connected with an end and a side and being spaced therefrom adjacent its apex.

60 2. In a device of the character described, the combination of a set of wooden members arranged to comprise a rectangular figure corresponding in dimensions substantially to the dimensions of the interior faces of 65 said member, the ends of said members be-

ing exposed, together with interior and exterior clamping devices arranged in sets to embrace the inner and outer faces of contiguous members adjacent their ends.

3. In a device of the character described, 70 the combination of a set of wooden members arranged to comprise a rectangular figure corresponding in dimensions substantially to the dimensions of the interior faces of said member, the ends of said members being exposed, together with interior and exterior 75 clamping devices arranged in sets to embrace the inner and outer faces of contiguous members adjacent their ends, said devices comprising right angled fittings enclosing with the ends of said members a substantially square and substantially unobstructed passage for air.

4. In a device of the character described, 80 the combination of a set of wooden members arranged to comprise a rectangular figure corresponding in dimensions substantially to the dimensions of the interior faces of said member, the ends of said members being exposed, together with interior and exterior 85 clamping devices arranged in sets to embrace the inner and outer faces of contiguous members adjacent their ends, said devices comprising right angled fittings enclosing with the ends of said members a substantially 90 square and substantially unobstructed passage for air, together with a bolt extending diagonally across said passage and connecting said fittings.

5. In a device of the character described, 100 the combination of a set of wooden members arranged to comprise a rectangular figure corresponding in dimensions substantially to the dimensions of the interior faces of said member, the ends of said members being exposed, together with interior and exterior 105 clamping devices arranged in sets to embrace the inner and outer faces of contiguous members adjacent their ends, said devices comprising right angled fittings enclosing with the ends of said members a substantially 110 square and substantially unobstructed passage for air, together with a bolt extending diagonally across said passage and connecting said fittings, said fittings being provided 115 with seats substantially normal to said bolt and adapted to receive abutment with nuts upon said bolt.

6. In a device of the character described, 120 the combination with the wooden sides of a cope and drag substantially in corner abutment with contiguous sides and having exposed ends, of inner and outer clamping devices angularly formed for engagement with the inner and outer faces at the ends of said 125 sides, said devices having less vertical extent than said sides, and fittings applied respectively to the clamping devices of the cope and the drag and including arms extending interiorly of their respective devices, said 130

fittings being formed for interaction, whereby properly to position the cope with reference to the drag.

7. In a device of the character described, 5 the combination with the wooden sides of a cope and drag said sides being respectively substantially in corner abutment with contiguous sides and having exposed ends, of inner and outer clamping devices angularly 10 formed for engagement with the inner and outer faces of the end portions of said sides, and spaced from said exposed ends, the outer

of said devices being spaced from the exposed ends of said sides, and the said clamping devices of the cope and drag being of 15 like construction, together with complementary interlocking elements comprising angle fittings having arms bolted detachably to the fittings respectively of the cope and of the drag and adapted when so bolted to interact 20 with each other to position the cope upon the drag.

GEORGE O. BERGSTROM.
